NECKTIE SHAPER AND FORMER

Roger Dennett, San Francisco, Calif.

Application November 12, 1943, Serial No. 509,973

1 Claim. (Cl. 2—153)

This invention relates to a form capable of being inserted between the folds of a knot of a necktie of the four-in-hand variety, to thus maintain the knot in the required adjusted position, to prevent a slipping of the knot and to provide a neat appearance of the tie under all conditions of strain.

The principal object of the invention is the provision of a dual locking arrangement of the form with relation to the folds of the tie, whereby the form will be detachably retained in fixed position within the folds and upward, downward and vertical movements of the form will be prevented, thus assuring an attractive shape to the tie, and eliminating any tendency of displacement from its efficient knot-shaping and forming operative position.

An additional object of the invention is the provision of an unique form of the knot shaper, wherein a core of plastic or similar material is employed that is equipped with an enlarged upper portion and a tapered lower portion, which upper portion of the core is so shaped that the contour of the same gives form to the sides and front portion of the knot of the tie, while the lower portion is reduced to eliminate bulkiness and to likewise conform to the shape of the reduced or lower portion of the tie knot.

An additional object of the invention is the production of a device of the character described, that is simple in construction, economical to manufacture, most durable, positive in operation, and one that can be easily inserted or readily removed from its operative position.

Other objects and advantages will be apparent during the course of the following description:

In the accompanying drawing forming a part of this specification and in which like numerals are employed to designate like parts throughout the same:

Fig. 1 is front elevation of the device, comprising the present invention.

Fig. 2 is a side elevation of the same.

Fig. 3 is a rear view of the article.

Fig. 4 is side view of a modified form.

Fig. 5 is rear view of the same.

Fig. 6 is a front view of the completed tie with the article in operative position within the knot of the tie, and

Fig. 7 is similar view of the completed tie and the device in operative position, the loose end of the tie being turned aside to thus disclose to advantage the penetration of the pin in the other end portion of the tie.

Referring to the drawing, the reference charac-

ter A designates a four-in-hand necktie having a free end portion B and a running or loose end portion C. The outer fold of the necktie that forms a portion of the knot is indicated by the numeral 5, while the inner fold is indicated by the numeral 6.

The knot shaper and former is preferably made of a plastic composition and is designated as a whole by the numeral 7. The said article embodies in its construction an enlarged upper portion defining a head 8, and a lower reduced portion 9. The front wall 10 is slightly curved and has protruding therefrom integrally formed downwardly projecting teeth 11, capable of impinging on and being detachably secured to the rear surface of the portion B directly beneath the knot.

It will be noted that the rear wall 13 of the head 8 of the device and the rear wall 14 of the reduced portion 9, are substantially straight.

As illustrated to advantage in Figs. 4 and 5, instead of an integral formation of the teeth with the device, I have employed a pair of pin points 15 that penetrate the body of the device, protrude through the front wall 10 and thus provide pointed ends 16 capable of engaging the fold of the tie, in the same manner as do the teeth 11.

Referring to the form, it will be noted that the lower portion is reduced in thickness and width, which construction is effective in eliminating any bulkiness in the lower end of the knot, which enlargement would be present if the lower portion 9, were of the same thickness and width as the head 8. There is thus provided a device that conforms to the shape of a conventional knot of a four-in-hand tie.

One of the main objects of the present invention is to prevent the accidental displacement of the form when it is in an adjusted or operative position, and to thus assure a dual locking of the form in the folds of the tie, I propose to employ a pin 17 that is secured to the lower extremity of the form and projects downwardly. The said pin 17 is receivable in the loose end portion C of the tie, and cooperates with the teeth 11 or the pointed ends 16, to prevent the accidental displacement or dislodgement of the form from the knot of the tie.

To effect a dislodgement of the device from the folds of the knot, downward movement of the slip or running end C of the tie will effect a release of the pin 17 from the portion C. An upward tilting of the lower end of the form with the right hand and retention of the lower fold of the tie with the left hand will release the teeth, and permit downward withdrawal of the article.

In the operation of the device, after the knot has been loosely tied, the article is slipped upwardly between the outer fold 5 and the inner fold 6 of the knot. The knot is then shaped and formed to the user's taste, and when the desired tension is obtained and the teeth 11 are impinged in the rear surface of the tie portion B, then the lower end of the tie is engaged by the pin 17.

I am aware of the fact that types of necktie shapers and retainers have been previously devised, but to my knowledge none possesses the unique construction of my article, wherein I accomplish the simplified and positive dual locking arrangement of the form within the folds of the knot of a necktie.

It is to be understood the forms of the invention herewith shown and described are to be taken as preferred examples of the same, and that changes relative to the shape, size, material and

arrangements of parts may be resorted to without departing from the spirit of the invention or the scope of the subjoined claim.

Having thus described my invention, I claim:

- 5 A necktie form of glazed material capable of fitting between the folds of the knot of a necktie of the four-in-hand variety, said form having an outer curved surface and a pair of inner surfaces differing one from the other in thickness and width, and fastening means positioned adjacent the respective ends of said form for detachably retaining the same in a knot shaping and forming position between the folds of the knot of the necktie, said means comprising integrally formed teeth 10 on the curved surface of the head of the form and a downwardly projecting pin carried by that portion of the form where the surface is of less thickness and width.
- 15

ROGER DENNETT.
